UNITED STATES PATENT OFFICE.

MARCUS O. ANTHONY, OF NEW YORK, N. Y.

MATCH-BOX.

No. 826,464.

Specification of Letters Patent.

Patented July 17, 1906.

Application filed June 2, 1905. Serial No. 263,432.

To all whom it may concern:

Be it known that I, MARCUS O. ANTHONY, a citizen of the United States, residing in the city of New York, borough of Manhattan, in the county and State of New York, have invented certain new and useful Improvements in Match-Boxes, of which the following is a specification.

The object of my invention is to produce a match-box, preferably of metal, involving the elements of simplicity and economy in construction and possessing marked utility and efficiency.

With these and other objects in view I construct the body of the box from a novel single piece-blank, preferably stamped out, and of such shape that the waste material incident to the stamping is very slight.

A further object of my invention is to so construct the box that matches may be readily withdrawn, individually or severally, therefrom without inverting the box or disturbing the main body of matches.

The invention will be fully understood from the following detailed description thereof, taken in conjunction with the accompanying drawings, wherein—

Figure 1 is a plan of one form of blank. Fig. 2 is a view, partly in section, of a box made from bending up said blank, the said box being provided with a cover. Fig. 3 is a bottom view of the box shown in Fig. 2. Fig. 4 is a modified form of blank. Fig. 5 is a perspective view of a box made from the blank shown in Fig. 4. Fig. 6 is still another type of blank; and Fig. 7 shows a box, partly in section, constructed from the blank illustrated in Fig. 6.

Referring now particularly to Figs. 1, 2, 3, and 3; A designates the whole blank, and B the completed box. The blank A is composed of the parts 10 and 11, which form the sides of the box, the intermediate section 12, which forms the back thereof, the end piece 13, which forms the front, the part 14, which forms the bottom, and the part 15, being an extension of 14, which serves the purpose of a spring to hold the cover in a closed or locked position. The bottom of the box 14 and the spring member 15, extending therefrom, are preferably corrugated, as shown at 16 16, to give them increased rigidity or stiffness. The bottom may be provided with a friction or match-striking surface 17, though it will be obvious that said surface may be applied to any part of the box. The

parts 10 and 11 of the blank are cut away at the upper front portions thereof, as shown at 18 19, so as to provide an inset or depression 20 in the upper front portion of the box 60 above the base of which the tops of the matches confined in the front part of the box project, thereby permitting the said matches to be readily withdrawn from the box.

In forming the body of the box from the blank A the spring member 15 is bent at right angles to the bottom part 14 along the dotted line 22, the bottom 14 is bent at right angles to the side 11 along the dotted line 23, 70 the back 12 is bent at right angles to side 11 along the dotted line 24 exteriorly of spring 15, and the side 10 is bent along line 25 into parallel relation with side 10, thus completing the sides, back, and bottom of the 75 box and the spring for the cover. The part 13 is then bent at right angles to part 11 along the line 27 to form the front of the box. It will be noted that the box thus formed has only three joints or seams, one where one 80 side of the front joins the side 10, (indicated at 26,) one where the front piece 13 joins the bottom, (indicated at 27,) and the third where the side 10 joins the bottom, (indicated at 28.) In order to secure tight joints or seams in 85 these places without employing solder, I make provision for forming lapped joints or seams, as clearly indicated in Figs. 1 and 2.

The box has a cover C, the sides of which, near the rear ends thereof, are provided with 90 ears or lugs 29, which rest in openings 30 in the sides of the box, thereby forming pintles or pivots on which the cover swings. These lugs may be easily formed by making a semi-circular cut in the metal and bending the 95 small free ends thus produced inwardly.

It will be noted that a box constructed as described has a well-finished appearance and that the spring thereof is confined within the box and is independent of the walls thereof.

The box illustrated in Figs. 4 and 5 differs from that shown in Figs. 1 to 3, in that the spring part or member 15 is dispensed with, the end 12' thereof, corresponding to the end 12, being slotted part way along its sides, as 105 shown at 31, whereby said part not only forms the back of the box, but serves also as a spring for the cover; otherwise it is constructed the same as the box shown in Figs. 1 to 3, the parts 10', 11', 13', and 14' thereof corresponding, respectively, to the parts 10, 11, 13, and 14.

In the form of the invention illustrated in Figs. 6 and 7 a blank is provided whereby the back of the box 12² also serves the purpose of a spring for the cover. 10² and 11² form the sides, and 13² the front, of the box, respectively. In shaping the box the sides 10² and 11² are bent into parallelism and at right angles to the front 13². The back and spring 12² are bent at right angles to the bottom 14² to and said bottom bent at right angles to side 11². A box thus constructed is without joints at the lines where the sides and front of the box meet.

In all forms of the invention the sides of the box are cut away near their upper front portions thereof, so as to leave an unobstructed space in the upper front part of the box when the cover is up, whereby matches in the front of the box are readily accessible.

20 In Figs. 4 to 6 the spring member may, if desired, be corrugated, as shown in Figs. 1 to 3.

The body of the box thus described is of such form that it may be stamped without substantial waste of material and may be readily bent into proper shape, thereby producing a box simply and economically and one presenting a substantial finished appearance.

It will be apparent that many slight changes may be made in the structure, as set forth herein, without departing from the spirit or sacrificing any of the advantages of the invention.

Having thus described my invention, what I claim, and desire to secure by Letters Patent, is—

1. As a new article of manufacture, a box-blank having the parts forming the sides, front, back and bottom of the box integral, and having a spring member attached to the part which is to form the bottom of the box, said member being independent of the part forming the back of the box.

2. As a new article of manufacture, a box-blank having the parts forming the sides, front, back and bottom of the box integral,

and having a spring member attached to the part which is to form the bottom of the box, said member being independent of the part forming the back of the box, but which can be folded into a position substantially parallel thereto.

3. As a new article of manufacture a metallic box-blank having the parts which are to form the sides, bottom, front and back of the box integral and having a spring member also integral with one of said parts but capable of being folded interiorly of the box.

4. As a new article of manufacture, a match-box having the members forming its sides, front, back and bottom integral, a cover-spring attached to one of said members and independent of the other members, and a cover adapted to be acted upon by said spring.

5. A match-box having its sides, front, back and bottom integral and formed from a single piece of metal, a spring member forming a continuation of the bottom and located interiorly of the box.

6. As a new article of manufacture, a match-box having its sides, front and back formed from a single continuous piece of metal, said parts being united by a single joint, a bottom, and a cover spring-pressed by an integral part of the box.

7. A match-box having its sides, front and back formed from a continuous piece of metal, and having only a single joint uniting said parts, a bottom forming a continuation of one of the sides of the box, a cover for the box, and a spring member integral with one of the parts of the box and arranged to bear against said cover so as to exert tension thereon.

In testimony whereof I have signed my name to this specification in the presence of two subscribing witnesses.

MARCUS O. ANTHONY.
